TOROIDAL COIL WINDING MACHINE

Malcolm O. Bennett, Methuen, and Henry E. Cradduck, Amesbury, Mass., assignors to Western Electric Company, Incorporated, New York, N. Y., a corporation of New York

Application January 4, 1950, Serial No. 136,696

16 Claims. (Cl. 242—4)

1

This invention relates to toroidal coil winding machines, and more particularly to hydroelectric automatically operable toroidal coil winding machines.

In the manufacture of toroidal coils, it is common practice to form layer windings on the core and the patent to A. L. Quinlan 2,341,650 has introduced bank winding in toroidal coils. The bank winding of the Quinlan structure is accomplished by the aid of a handle on the core chuck for manual oscillation of the core chuck between variable limits solely under the control of the operator to create bank winding on portions of the core.

An object of the present invention is to provide a toroidal coil winding machine capable of the conventional layer winding and of selectively forming right or left bank windings on a core.

With this and other objects in view, the invention comprises a toroidal coil winding machine having a core chuck to support a toroidal core at a given position relative to a shuttle, for a supply of strand material to be wound on the core, driven in a circular path through the core, a rocking shaft having the support mounted thereon whereby the center of the core will be coincident with the axis of the shaft. The rocking shaft is driven between variable limits by a means capable of forming different types of winding of the strand material on the core.

More specifically, the operation of the shuttle and the core chuck are under the control of hydroelectric means, arranged whereby through the actuation of one switch, the strand material will be wound in smooth continuous layers back and forth between the limits on one side of the coil through a total rotation of 180° forming what is known as layer winding on the core. Through the operation of another switch, right bank winding of the strand material is formed on approximately 90° of the core during shorter rotations of the rocking shaft. The hydroelectric means rotates the core chuck quickly to its starting position, moves it slowly for a given distance, quickly reverses back toward the starting position, stops and again rotates slowly in the winding direction. This process repeats until the core has rotated through approximately 90°. The amount of travel of each bank is short when close to the ends of the winding and a full length

between these end portions. By operating another switch, left bank winding is formed over approximately 90° of the core in a similar manner but in reverse directions as is required for the right bank winding. These respective windings are formed on the remaining portions of the cores by changing the positions of the cores in the core chuck.

Other objects and advantages will be apparent from the following detailed description, when considered in conjunction with the accompanying drawings, wherein:

Fig. 1 is a fragmentary side elevational view of the toroidal coil winding machine;

Fig. 2 is a schematic illustration of a portion of the control mechanism;

Fig. 2A is a schematic illustration of the remaining portion of the control mechanism;

Fig. 2B is an enlarged fragmentary isometric view of a portion of the control mechanism;

Fig. 2C is an enlarged sectional view of the control table and rack;

Figs. 3 and 3A combined compose a wiring diagram of the electrical features of the machine;

Fig. 4 is a fragmentary top plan view of the core chuck and core illustrating the formation of layer winding;

Fig. 5 is a fragmentary top plan view of the core chuck and core illustrating right bank winding; and

Fig. 6 is a fragmentary top plan view of the core chuck and core illustrating left bank winding.

Referring now to the drawings, attention is first directed to Fig. 1 which illustrates a core chuck 20 having relatively movable jaws 21 and 22 to firmly clamp a core 23 therebetween. The mechanism for actuating the jaws 21 and 22 is disposed in a housing 24 and is under the control of a hand lever 25, this mechanism being disclosed in a copending application Serial No. 75,644, filed February 10, 1949, now Patent No. 2,608,892. The housing 24 is mounted on the upper end of a rocking shaft 26 journaled in suitable bearings 27 and having a sprocket 28 mounted thereon and operatively connected thereto through a spring pressed ball 29 of a chuck 30.

A shuttle 33, for receiving a supply of strand material such as insulated wire 34, is supported for rotation through the core 23 to wind the

strand material on the core. Rotatably mounted rollers 35 and 36 support the shuttle 33, the rollers 35 being free to rotate while the roller 36 is fixedly mounted on a shaft 37 to be driven by the mechanism hereinafter described. The rollers 35 may be provided with the conventional gear teeth for positive connection with an inner ring gear on the shuttle. The shuttle and the supporting rollers are of the conventional type and further detailed description thereof is not believed necessary.

Attention is now directed to Figs. 2 and 2A which show the mechanical and hydraulic means for operation under the control of the electrical circuits shown in Fig. 3. The sprocket 28 for the chuck 20 shown at the lower portion of Fig. 2A is driven by a chain 40 having its ends connected to the opposing ends of piston rods 41 and 42 of a piston 43 in a cylinder 44. The chain 40 also travels about a sprocket 45 mounted on a shaft 46 which has a sprocket 47 mounted on the opposite end thereof. A chain 48 extends about the sprocket 47 and has one end connected to the adjacent end of a stop bar 49 and the other end connected to the adjacent end of a control table 50. The control table 50 is mounted in a groove 51 of a support 52 for movement longitudinally in a guided path therein (Fig. 2C). A similar idler sprocket 53 has a chain 54 extending therearound with its ends connected respectively to the stop bar 49 and the control table 50. The stop bar is of a given length and has stops 56 and 57 mounted at selected positions thereon, the main portions of the stops having switch engaging surfaces 58 and 59, while their outer portions are of reduced thicknesses providing offset surfaces 60 and 61. The surface 58 of the stop 56 is positioned to actuate limit switches 64 and 65, while the surface 59 of stop 57 is positioned to actuate limit switches 67 and 68. The surface 60 of the stop 56 is positioned to actuate a limit switch 70, while the surface 61 of stop 57 is positioned to actuate a limit switch 71.

The control table has a longitudinal groove 72 in its upper surface and limit switches 73 and 74 mounted at the ends thereof, positioned to be actuated by the respective ends of a rack 75 supported in the groove 72 for movement relative to the control table and the limit switches 73 and 74. The rack is engaged by a pinion 78 on a shaft 79 which is driven by pawls 80 and 81 and ratchets 82 and 83 upon energization of solenoids 84 and 85 respectively. The shaft 79 is supported by stationary bearings 86 and provided with a predetermined constant braking force at 87, whereby the pinion 78 will be disposed at a fixed position holding the rack 75 against movement with the control table 50 and under the complete control of the solenoids 84 and 85. Looking toward the ends of the shaft 79, the units, including the solenoid operable pawls and sprockets, are in this embodiment of the invention the same as that shown in Fig. 2B. Although these units are the same, they function to rotate the shaft 79 in opposite directions. The unit shown in Fig. 2B includes the core for the solenoid 84 connected to the free end of a pivoted lever 88 by a link 88'. The lever 88 is normally held against a stop 89 by a spring 89'. The pawl 80, which is pivotally supported by the lever 88 intermediate its ends, is normally urged counterclockwise against its stop 89' by its spring 89''. In the normal positions of the units with the solenoids 84 and 85 deenergized, the pawls 80 and 81 are away from

their sprockets leaving the shaft 79 under the control of a brake 87. The brake 87 applies a given holding force to the shaft to cause the pinion 78 to hold the rack 75 against movement with the control table during reciprocation thereof. However, the rack may be moved in either direction with or against the movement of the control table 50 through the energization of either solenoid 84 or 85 and the operation of their respective pawls and ratchets. Upon de-energization of the solenoids the pawls are immediately returned to their normal positions free of their ratchets.

Attention is now directed to Fig. 2A which discloses a portion of the power means for operating the machine. An electric motor 90 has its shaft 91 connected to an input shaft 92 of a hydraulic unit 93 through a coupling 94. The hydraulic unit is of a commercially known type having an output shaft 95 and under the control of foot pedal 96 whereby the unit will give an output speed or rotary movement to the output shaft 95 of zero to six hundred revolutions per minute with a constant maximum torque. The output shaft 95 is connected to a one-way clutch 97 and through the clutch to a gear pump 98 and a piston pump 99 through a sprocket and chain connection 100. The gear pump 98 and the piston pump 99 are commercial units and their detailed structure need not be shown. An indicating unit 102 is connected through shafts 103 and 104 and intermediate gears 105 to the piston pump 99 to register the output of the pump.

The one-way clutch 97 drives a shaft 107, a sprocket and chain connection 108 and a shaft 109 which is connected to a shaft 110 through a magnetic clutch 111. The shaft 37, driving the shuttle 33, is operatively connected to the shaft 110 through beveled gears 112, the conventional connecting mechanism for the shuttle being under the control of a hand wheel 114. A counter unit 115 to indicate the revolutions of the shuttle is driven through a sprocket and chain connection 116 from the shaft 110. An arm 118 shown in Figs. 1 and 2a, constituting a part of the shuttle mechanism, is positioned to operate a safety switch 119 when the shuttle mechanism is in readiness for operation.

The motor 90 drives a rapid traverse gear pump 122 through gears 123 and 124. The pump 122 is connected to a supply tank 125, which is to contain the main supply of fluid such as oil for use in the hydraulic system, this connection being embodied in line 126. The outlet of the rapid traverse gear pump 122 is indicated at 127 and connects with lines 128 and 129 of solenoid valves 130 and 131. The valves 130 and 131 are shown in their normal or deenergized positions.

Referring first to solenoid valve 130, it will be noted that line 128 communicates with passageway 134 and through line 135 to the top of the cylinder 44, while the other passageway 136 connects a line 137 from the bottom of the cylinder 44 with a line 138 which leads to the solenoid valve 131. When the solenoid 130 is energized, the lines are in a sense reversed in that the passageways 134 and 136 are replaced by passageways 140 and 141, passageway 140 connecting lines 135 and 138, and passageway 141 connecting lines 128 and 137.

When the solenoid valve 131 is in its normal or deenergized position, line 138 will be connected to a line 144 through a passageway 145 which enters a line 146 between relief valves

147 and 148, extending from the piston pump at 149 to the bottom of the tank 125 at 150. The line 129 is connected through a passageway 152 to a line 153 leading to the bottom of the tank 125. An arcuate passageway 155 connects lines 129 and 144 when the solenoid valve 131 is energized and at the same time an arcuate passageway 156 connects lines 138 and 153.

A supply line 160 leads from the tank 125 to the supply portions of the gear pump 98. An output line 161 for the pumps 98 and 99 is connected to a line 162, a portion of which extends upwardly to the hydraulic unit 93, while another portion extends through a relief valve 163 to the bottom of the tank 125 at 164.

Attention is now directed to Fig. 3 which illustrates the wiring diagram of the electrical circuits of the control mechanism for the machine. At the top of the figure, the supply lines 165 for the motor 90 are shown including a start switch 166. In the present embodiment of the invention, the other circuits include lines 170 and 171 supplied with a suitable electrical energy from a transformer 172. The magnetic clutch 111 is in a circuit from line 170 at connections 173 and 174 through rectifiers 175 and 176 in parallel, suitable resistances 178, safety switch 119 when closed, and normally closed contacts 180 in the counter unit 115, to line 171 at connection 181.

There are four manually operable switches, the selective operation of which determines the type of winding to be performed by the machine. A switch 200 is included in a circuit with the winding of a relay 201 having break contacts 202, 203 and 204 and make contacts 205, 206, 207, 208 and 209. A switch 210 is in a circuit with the winding of a relay 211 having break contacts 212, 214, 215 and 216 and make contacts 217, 218, 219 and 220. The switches 200 and 210 are of the type which remain in any position in which they are disposed until they are moved into another position, while switches 225 and 226 are of the type which are normally open and will return to open position when released. The switch 225 is in a circuit with the winding of a relay 227 which has break contacts 228, 229 and 230 and make contacts 231 and 232. The switch 226 is in a circuit with the winding of a relay 235 which has break contacts 236, 237 and 238 and make contacts 239 and 240. The wiring diagram, including the various electrical circuits will be explained more in detail during the description of the operation of the machine.

Upon considering the operation of the machine for winding any of the forms shown in Figs. 4, 5 and 6, it is necessary that the core 23 be clamped in the core chuck 20 and that the shuttle 33 be supplied with the necessary amount of wire or strand material 34. These operations are performed in the conventional manner, an added precaution being embodied in the safety switch 119 under the control of the arm 116 which is in a position to close the switch when the shuttle is ready for operation. Let it be assumed that the machine is to perform layer winding as shown in Fig. 4. This may be accomplished by first closing the switch 166. The switch 225 is then closed completing a circuit from line 170, at connection 245, through switch 225, winding of relays 227 and connection 246 to line 171 at connection 247. Energization of the relay 227 will break contacts 228, 229 and 230 and make contacts 231 and 232. A single contact 250 is under the control of a double relay having a latch winding 251 and a

trip winding 252. When contact 231 of relay 227 is closed, a circuit is completed from line 170 at connection 253, through a break contact 254 of a relay 255, through contact 231, winding 252, connection 256 to line 171 at connection 247. Energization of the winding 252 assures opening of the contact 250 which is in a circuit including the solenoid 130, this circuit extending from line 170 at connection 258 through contact 250 when closed, solenoid 130 to line 171 at connection 259. Furthermore, the making of contact 232 energizes the solenoid valve 131 completing a circuit from line 170 at connection 253 through break contact 254, connection 260, contact 232, connection 261, solenoid 131, to line 171 at connection 262. In the present instance therefore, the solenoid valve 131 is energized while the solenoid valve 130 is deenergized causing a rapid movement of the core chuck 20 clockwise or to the left. The gear pump 122 is always pumping oil at a rapid rate from line 126 through line 127. When the solenoid valve 131 is deenergized, this oil is allowed to pass through line 129, passageway 152 and line 153 to the main supply tank 125. However, when the solenoid valve 131 is energized, line 129 is connected through passageway 155 to lines 144 and 146. This results in cutting off the escapement of the oil from the rapid traverse pump 122 to the tank 125 and adds it to the oil from the pumps 98-99 through line 128, and the selected passageway 134 or 136 in the valve 130 to cause rapid return movement of the piston 43 with the chuck 20 and core 23. Furthermore, energization of the solenoid valve 131 connects line 138 through passageway 156 and line 153 to the tank 125 for a rapid exhausting of the oil on the opposite side of the piston 43.

The rapid return of the chuck 20, for example to the left, through the operation of the piston 43 causes the shaft 46 to rotate, moving the mechanism shown in Fig. 2 until the stop 56 or the surface 58 thereof closes limit switches 64 and 65. Closing of limit switch 64 results in the energization of the relay 255 by completing a circuit from line 170 at connection 265, through break contact 202, limit switch 64, relay 255 to line 171 at 262, energizing the relay to break contact 254. Although the winding 252 is deenergized, contact 250 will remain open. However, breaking of contact 254 results in the deenergization of the solenoid valve 131, stopping the movement of the piston 43 and the chuck 20 and locating the chuck with the core at the starting position. At this time, the operator having conditioned the machine for layer winding, locating the core chuck at the left starting position, the switch 225 is released, the limit switches 64 and 65 remaining closed and relay 227 being deenergized allowing the contacts thereof to return to their normal positions. The operator then presses the pedal 96 causing oil to flow from the piston pump 99 through line 149, relief valve 147, line 144, passageway 145, line 138, passageway 136 and line 137, to the lower portion of the cylinder 44. The speed of movement of the piston in the cylinder and likewise the speed of movement of the chuck is under the control of the pump 99 which is under the direct control of the hydraulic unit 93. The gear pump 98 and the piston pump 99 are driven at a speed directly proportional to the output speed of the hydraulic unit. The gear pump 98 supplies makeup oil to the hydraulic unit 93 through the upper portion of line 162 and supplies oil to the piston pump 99 at approximately fifty pounds pressure. The pis-

ton pump 99 may therefore be called a feed pump as it moves the core chuck 20 whenever the hydraulic unit is driving the shuttle forward or in the winding direction. Due to the one way clutch 97, the pump 99 will not move the chuck while the shuttle is rotating in the opposite direction unless solenoid 131 is energized and the rapid traverse pump flow is used. The solenoid valve 130 merely provides for a two directional movement of the piston 43 and the chuck 20.

As soon as the operator presses the foot pedal 96 and the fluid to the cylinder 44 causes movement of the chuck to the right or counterclockwise, the stop 56 is moved away from the limit switches 64 and 65 opening the circuit to the relay 255 and allowing its contact 254 to close. This operation continues during the winding of a layer of wire on the core during rotation of the core through approximately 180° until the stop 57 through its surface 59 closes the limit switches 67 and 68. Closing of limit switch 67 completes a circuit through the winding of a relay 281 from line 170 at connection 265, through break contact 202 of relay 201, connection 282, limit switch 67, relay 281 to line 171 at connection 247. Energization of the relay 281 opens its break contact 283. The closing of the limit switch 68 energizes the winding 251 of the double relay closing the contact 250 by completing a circuit from line 170 at connection 285 through break contact 229 of relay 221, break contact 237, of relay 235, through limit switch 68, break contact 203 of relay 201, through the winding 251, connection 256 to line 171 at connection 247. Energization of the winding 251 completes the circuit through the solenoid valve 130 reversing the flow of the oil. The mechanism driven by the piston 43 will start movement of the core chuck 20 in the reverse direction starting another layer of winding on the core. At the same time the stop 57 moves away from the limit switches 67 and 68, the circuit to the relay 281 opens resulting in the closing of the contact 283. The winding 251 also deenergizes, but the contact 250 remains closed as it will not be opened until the winding 252 is energized.

The operation continues until the stop 56 closes the limit switches 64 and 65. The switch 64 when closed energizes the winding of relay 255, opening contact 254 while the switch 65 when closed completes the circuit through the winding 252 to open the contact 250, deenergizing the solenoid 130 to again reverse the direction of flow of the oil to the cylinder 44. The circuit completed through the winding 252 by closing limit switch 65 may be traced from line 170 at connection 285 through break contact 229 of winding 221, break contact 237 of winding 235, connection 306, switch 65, break contact 204 of winding 201, through winding 252 to line 171 at connection 247. This operation continues as long as the foot pedal is actuated forming repeated layers of strand material or wire on the core. During this operation, the operator determines the number of convolutions or windings on the core by observing the counter 115 which registers the number of revolutions of the shuttle 33. This completes the description of the operation of the winding machine to wind layers of wire on the core as shown in Fig. 4, the windings starting from the left.

If it should be desirable to form layer windings on the core starting from the right, the operator initially, instead of closing the switch 225 as 75

previously described, closes the switch 226 which completes a circuit through a relay 235 from line 170, at connection 286, through switch 226, relay 235, connection 287 to line 171 at connection 247. Energization of the relay 235 breaks contacts 236, 237 and 238 and makes contacts 239 and 240. The winding 251 of the double acting relays for contact 250 is energized by the closing of a circuit from line 170 at connection 289 through contact 283, closed contact 240, winding 251, connection 256 to line 171 at connection 247. Energization of the winding 251 closes the contact 250 energizing the solenoid valve 130, causing the flow of oil to the cylinder 44 to result in the movement of the core chuck to the right or counterclockwise so that during the subsequent operations, the shuttle 33 will begin winding the strand on the core while the core travels first to the left to wind the first layer of wire on the core. The subsequent operations are similar to those previously described, the stops 56 and 57 and their associated limit switches 64—65 and 67—68 reversing the travel of the core chuck at the completion of each layer of convolutions.

When it is desirable to form bank winding on the core, the core may be provided with dividers 290 of insulating material to separate the core for four windings. The first step taken in the operation of the machine for bank winding is the closing of switch 200 which converts the machine from layer winding operations to bank winding operations. By closing the switch 200 a circuit is completed from line 170 at connection 291, through switch 200, relay 201, connections 292 and 246 to line 171 at connection 247. Energization of relay 201 breaks contacts 202, 203 and 204 and makes contacts 205, 206, 201, 208 and 209. The winding 251 of the double acting relay for contact 250 is energized to close the contact by the closing of a circuit from line 170 at connection 285, through contact 229 of relay 221, contact 237 of relays 235, contacts 207 and 206, successively of relay 201, contact 212 of relay 211, through connection 293, winding 251, connection 256 to line 171 at connection 247. This circuit, when closed, closes contact 250 and energizes the solenoid valve 130.

Let it now be assumed that it is desirable to do right bank winding as shown in Fig. 5. To locate the core chuck 20 at the starting position, switch 225 is pressed completing the circuit through the relays 221 energizing the relay to break contacts 228, 229 and 230 and to make contacts 231 and 232. This action deenergizes the winding 251 which effectively allows the contact 250 to remain closed. However, the winding 252 is energized by the closing of contact 231 and the contact 250 is opened, deenergizing the solenoid valve 130. The solenoid valve 131 is energized by the closing of contact 232 resulting in causing the piston 43 to move the core chuck to the left.

During the description of the operation of the machine for layer winding as shown in Fig. 4, no mention was made of the fact that limit switches 73 and 74 close at various times, the reason being that their circuits remain open at contacts 208 and 209 of relay 201. The control table and the associated mechanism functions only during bank winding operations at which time the limit switches 73 and 74 are under the control of the rack 15 and added to the controls of the stops 56 and 57 to bring about the desired movements of the core chuck to create bank winding on the core. It will be understood that without energization of the solenoid 84 or

85, the pinion 78 would hold the rack 75 against movement and movement of the control table 50 relative thereto during rocking movement of the core chuck and simultaneous movement of the stop bar 49 with its stops 56 and 57, would cause the roller carrying arms of the limit switches 73 and 74 to alternately ride upon their respective ends of the rack 75 and be actuated into closed positions. Furthermore, the time intervals between operations of the limit switches 73 and 74 would be constant if the solenoids 84 and 85 were not operated. Therefore, these time intervals may be varied by the energization of either solenoid 84 or 85 to actuate its pawl 80 or 81 to rotate the shaft 79 to move the rack 75 toward or away from the limit switches 73 and 74. Through this means, it is possible to vary the length of rocking movement of the core chuck and core, particularly at the ends of the bank windings to fill up the corners of the windings.

Returning to the last step described where the switch 225 had been pressed into closed position energizing relay 227, deenergizing winding 251, energizing winding 252 to open contact 250 to deenergize solenoid 130 and energize solenoid 131, resulting in rapid movement of the core chuck and core to the left. During this interval, the limit switch 73 rides upon the rack 75 and closes, but nothing happens. Furthermore, stop 56 closes limit switches 64 and 65 and nothing happens, the operation continuing until the surface 60 of stop 56 engages limit switch 70 and moves it into closed position. A circuit is then completed through relay 255 from line 170 at connection 265, through connection 300, closed contact 205 of relay 201, connection 301, limit switch 70, relay 255 to line 171 at connection 262. Energization of relays 255 and open contact 254, deenergizing winding 252 of the double acting relay at which time, the contact 250 remains open. Furthermore, solenoid 131 deenergizes through the opening of the contact 254 diverting the oil to the tank 125 stopping movement of the chuck 20 at the left where it remains stationary.

The necessary functions to set the machine for right bank winding having been completed, the operator releases the switch 225, opening the circuit to relay 227 allowing its contacts 228, 229 and 230 to close and contacts 231 and 232 to open. A circuit to a relay 304 is completed from line 170 at connection 285, through contact 229 of relay 227, contact 237 of relay 235 through connection 306, limit switch 65, connection 307, contact 209 of relay 200, connection 308, contact 216 of relay 211 through relay 304 to line 171 at connection 309. Energization of the relay 304 opens its contact 310 which is included in a circuit hereinafter described.

Another double acting relay has windings 311 and 312 creating opposing actions on their contacts 313 and 314, the winding 311 opening the contacts simultaneously when energized where they will remain open until the winding 312 is energized causing them to close where they will remain closed until the winding 311 is again energized. Deenergization of the relay 227 also completes a circuit through the winding 312, this circuit including the major portion of the circuit previously described for relay 304 and extending from connection 315 through break contact 316 of relay 317, through winding 312, connections 318, 319 and 320 to line 171 at connection 309. At the same time, winding 251 is energized closing contact 250 to energize solenoid valve 75

130. The circuit through the winding 251, upon deenergization of the relay winding 229, may be traced from line 170 at connection 285, through contact 229 of winding 227, contact 237 of winding 235, connection 306, contacts 207 and 206 of winding 201, contact 212 of winding 211, connection 293, winding 251, connection 256 to line 171 at connection 247. During the interval of time, solenoid 85 operates and through its pawl and ratchet 81—83, the rack 75 is moved toward the limit switch 73. The circuit for the solenoid 85 is completed from line 170 at connection 285, through contact 229 of winding 227, contact 237 of winding 235, connection 306, contact 207 of winding 201, contact 313 of winding 312, contact 236 of winding 235, contact 228 of winding 227, contact 214 of winding 211, solenoid 85, connections 330 and 331 to line 171 at connection 247. Eventually the solenoid 131 is energized when the limit switch 73 is closed whereby the rapid flow of oil will return the chuck rapidly to the right. When the switch 73 is closed a circuit is completed from line 170 at connection 285, contact 229 of winding 227, contact 237 of winding 235, connection 306, switch 65, connection 307, contact 209 of winding 201, switch 73, contact 314 of winding 312, contact 238 of winding 235, contact 236 of winding 227, solenoid 131 to line 171 at connection 262. When this takes place, the stop 56 releases the limit switch 70 allowing it to open and deenergize relay 255 resulting in the closing of the contact 254. Furthermore, the rack 75 releases the limit switch 73 allowing it to open. Stop 56 then releases limit switches 64 and 65, both of which will open resulting in the deenergization of relay 304 and the closing of its contact 310. Furthermore, winding 312 is deenergized and contacts 313 and 314 remain closed.

The next step in the operation includes the closing of the limit switch 74 by the rack 75 due to the movement of the table 50. At this time the relay 317 is energized, a circuit having been completed from line 170 at connection 285, through contact 229 of relay 227, contact 237 of relay 235, connection 306, contact 207 of relay 201, limit switch 74, connection 322, contact 215 of relay 211, connection 323, relay 317 and connections 319 and 320 to line 171 at connection 309. Energization of the relay 317 opens its contact 316. The winding 311 energizes and causes opening of the contacts 313 and 314. The circuit through the solenoid 85 is opened on opening contact 313 which opens a circuit from line 170 at 285 through contacts 229, 237, 207, 313, 236, 228 and 214 through the solenoid 85, connections 330, 331 to line 171 at 247. Solenoid 131 is deenergized by opening of contact 314 resulting in the flow of the oil from the gear pump 122 to the tank 125 and thus stopping the flow of oil to the cylinder 44. The core chuck is stopped in this position where it is ready for the right bank winding. At this time, the operator presses down on the foot pedal 96 causing oil to flow through lines 149, 148 and 144 through solenoid 131 deenergized and solenoid 130 energized moving the piston 43 in the cylinder 44 slowly in a direction to move the core chuck to the left. During this operation, the rack 75 during relative movement of the control table and the rack causes actuation of the switch 74 to complete a circuit through winding 311 to hold the contacts 313 and 314 open. At the same time, relay 317 is energized under the control of the limit switch 74 opening the contact 316. During the next interval of operation, depending upon the relative position

of, first, the rack 75 with respect to the limit switch 73, or second, the relative position of the stop 56 with respect to the limit switches 64 and 65, first limit switch 73 or limit switches 64 and 65, first limit switch 73 or limit switches 64 and 65 will close, but since limit switch 64 will have 5 no effect and limit switches 73 and 65 are in parallel, then that effect will be the same. As the bank winding progresses, stop 56 will be further from limit switches 64 and 65 so that after a few banks of windings, limit switch 73 10 will be the actuating switch until the end of the bank is wound.

Returning to the present portion of the operation, stop 56 closes limit switches 64 and 65 at which time relay 304 energizes opening its contact 310. Winding 312 of the double acting relay energizes closing contacts 313 and 314. At the same time solenoid 85 energizes operating its pawl 81 and ratchet 83 to advance the rack toward the limit switch 73 and away from limit switch 74. Also solenoid 131 energizes to cause a rapid return of the core chuck to the right. When this takes place, stop 56 moves free of the limit switches 64 and 65 allowing them to open at which time relay 304 deenergizes closing contact 310. The winding 312 of the double acting relay also deenergizes, but the contacts 313 and 314 remain closed. During the rapid reverse of the core chuck, the limit switch 74 rides upon the rack 75 and is operated into closed position. Relay 317 energizes opening its contact 316 and winding 311 of the double acting relay energizes opening the contacts 313 and 314. At this time solenoid 131 deenergizes diverting the flow of the oil from the rapid traverse pump 122 and through 30 the control of the fluid from pumps 98 and 99, the core chuck moves slowly to the left. The core chuck moves slowly to the left. The limit switch 74 when moved free of the rack 75 is allowed to open and relay 317 is deenergized 35 opening its contact 316. At the same time, the winding 311 deenergizes, but the contacts 313 and 314 remain open. It will be noted that since the rack 75 has been moved toward limit switch 73, at the same time stop 56 is moved away from limit switches 64 and 65, the rack will close limit switch 73 instead of stop 56 closing limit switches 64 and 65. During the next series of steps, relay 304 energizes opening its contact 310 and the winding 312 energizes closing the contacts 313 and 314. The solenoid 85 will then be energized effectively advancing the rack 75 toward the limit switch 73. The solenoid 131 then energizes again causing a rapid reverse of the core chuck. At the completion of the rapid reverse movement of the core chuck, limit switch 73 will be closed and this cycle will be repeated causing the winding of a given number of convolutions forming the banked layers on the core until stop 57 closes limit switches 67 and 68 instead of the rack 75 closing the limit switch 73. At that time, the bank of winding becomes shorter to fill in the corners as shown in Fig. 5 of the drawings. The machine is automatically stopped when the winding is completed at which time limit switches 73, 67 and 68 will be closed. The machine may also be stopped at this time or at any other time by returning the foot pedal 96 to its neutral position.

To set up the machine for operation in left bank winding instead of right bank winding, the foot pedal is returned to its zero or normal position and the necessary arrangement is made for mounting the core in the core chuck for left bank winding of the strand material thereon. It is not believed necessary to carry out the descrip-

tion for the complete winding of each core as it is understood that the winding of one-half the core in layer winding may be repeated on the other half the core to complete the winding of the core. Furthermore, in the description of the right bank winding, only one-fourth of the core was covered through the operation of the machine as previously described, but this operation may be repeated until the core is filled.

The first step in converting the machine from right bank winding to left bank winding is the closing of switch 210 which completes a circuit from line 170 at 335, through switch 210, through the winding of relay 211 connection 236 to line 271 at connection 247. Energization of the relay 211 opens its contacts 212, 214, 215 and 216 and closes its contacts 217, 218, 219 and 220. The winding 251 of the double acting relay is deenergized by the opening of contact 212, but the contact 250 remains closed. However the winding 252 of this relay is energized by the closing of contact 217 opening the contact 250 and deenergizing the solenoid 130. The operator at this time presses the switch 226 into closed position completing a circuit from line 170 at connection 286 through relay 235, connection 287 to line 171 at connection 247. Energization of the relay 235 opens its contacts 236, 237 and 238 and closes its contacts 239 and 240. The winding 251 of the double acting relay energizes by the closing of contact 240, completing a circuit from line 170 at connection 289 through contacts 283 and 249, winding 251, connection 256 to line 171 at connection 247. The contact 250 is thus closed energizing the solenoid valve 130. The solenoid valve 131 is also energized by the closing of the contact 239, the circuit being completed from line 170 at connection 289 through contacts 283 and 233 through connection 261, solenoid 131 to line 171 at connection 262.

The operation of the machine for left bank winding is very similar to the operation of the machine for right bank winding with the exception that the rapid and slow movements of the core chuck are reversed, thus reversing the lays of the bank windings on the core. Furthermore during the previous description for right bank winding, the controls for the movement of the core chuck were embodied in the limit switch 73, the limit switches 64, 65 and 70 under the control of the stop 56 and the operation of the solenoid 85. For left bank winding, the operation is substantially the same with the exception that the controls for the movement of the chuck are embodied in the limit switch 74 and its relationship with the rack 75, the limit switches 67, 68 and 71 and their relationship with the stop 57 and also the operation of the solenoid 84. In each instance during bank winding operations, rocking motions are imparted to the core to fill the starting corners, these motions increasing in length until the main rocking distance is reached after which repeated operations result in the winding of banked layers or convolutions of the wire on the core until the opposite end of the portion of the core is reached at which time shorter rocking motions are imparted to the core to fill up the corner.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. A toroidal coil winding machine comprising a chuck to support a toroidal core at a given position, a shuttle for a strand to be wound on the core, supported for movement in a circular path through the core, a rocking shaft having the chuck mounted thereon whereby the center of the core will be coincident with the axis of the shaft, a fluid operable unit to rock the shaft, and valves operated in a given sequence to control the flow of fluid to the unit to control the direction of movement of the shaft with the chuck and core relative to the shuttle.

2. A toroidal coil winding machine comprising a chuck to support a toroidal core at a given position, a shuttle for a strand to be wound on the core, supported for movement in a circular path through the core, a rocking shaft having the chuck mounted thereon whereby the center of the core will be coincident with the axis of the shaft, a fluid operable unit to rock the shaft, and valves operated in a given sequence operable to force a fluid into the unit to cause it to rock the shaft at a given speed whereby convolutions of the strand will be uniformly wound on the core from a starting position.

3. A toroidal coil winding machine comprising a chuck to support a toroidal core at a given position, a shuttle for a strand to be wound on the core, supported for movement in a circular path through the core, a rocking shaft having the chuck mounted thereon whereby the center of the core will be coincident with the axis of the shaft, a fluid operable unit to rock the shaft, a unit operable whereby a fluid under pressure may be directed into the unit to cause it to rock the shaft at a given speed whereby convolutions of the strand will be uniformly wound on the core from a starting position, a rapid reverse unit, and a valve to render the rapid reverse unit operable to cause a fluid to flow at a given velocity and pressure to the fluid operable unit to cause it to reverse the shaft with the chuck and core rapidly toward the starting position.

4. A toroidal coil winding machine comprising a chuck to support a toroidal core at a given position, a shuttle for a strand to be wound on the core, supported for movement in a circular path through the core, a rocking shaft having the chuck mounted thereon whereby the center of the core will be coincident with the axis of the shaft, a piston operatively connected to the shaft to rock the shaft through given degrees of rotation relative to a starting position, a power unit having a selectively variable output, means operatively connected to the power unit to drive the shuttle, and a fluid pump driven by the output of the power unit to force a fluid under varying pressures to the piston whereby the shaft with the chuck and core will be rocked from a starting position at a speed variable with variations in the speed at which the shuttle is driven to uniformly wind the strand on the core.

5. A toroidal coil winding machine comprising a chuck to support a toroidal core at a given position, a shuttle for a strand to be wound on the core, supported for movement in a circular path through the core, a rocking shaft having the chuck mounted thereon whereby the center of the core will be coincident with the axis of the shaft, a piston operatively connected to the shaft to rock the shaft through given degrees of rotation relative to a starting position, a power unit having a selectively variable output, means operatively connected to the power unit to drive

the shuttle, a fluid pump driven by the output of the power unit to force a fluid under varying pressures to the piston whereby the shaft with the chuck and core will be rocked from a starting position at a speed variable with variations in the speed at which the shuttle is driven to uniformly wind the strand on the core, and a rapid traverse pump to force a fluid under a given high pressure to the piston to cause it to rock the shaft with the chuck rapidly toward the starting position.

6. A toroidal coil winding machine comprising a chuck to support a toroidal core at a given position, a shuttle for a strand to be wound on the core, supported for movement in a circular path through the core, a rocking shaft having the chuck mounted thereon whereby the center of the core will be coincident with the axis of the shaft, a piston operatively connected to the shaft to rock the shaft through given degrees of rotation relative to a starting position, a power unit having a selectively variable output, means operatively connected to the power unit to drive the shuttle, a fluid pump driven by the output of the power unit to force a fluid under varying pressures to the piston whereby the shaft with the chuck and core will be rocked from a starting position at a speed variable with variations in the speed at which the shuttle is driven to uniformly wind the strand on the core, a rapid traverse pump to force a fluid under a given high pressure to the piston to cause it to rock the shaft with the chuck rapidly toward the starting position, a valve actuatable to direct the fluid from the said fluid pump to either side of the piston to cause the shaft with the chuck and core to move in either direction at selectively variable speeds, and an auxiliary valve actuatable to direct the fluid under high pressure from the rapid traverse pump to the reversing side of the piston to cause the shaft with the chuck and core to move rapidly toward the starting position.

7. A toroidal coil winding machine comprising a chuck to support a toroidal core at a given position, a shuttle for a strand to be wound on the core, supported for movement in a circular path through the core, a rocking shaft having the chuck mounted thereon whereby the center of the core will be coincident with the axis of the shaft, a unit actuatable to rock the shaft with the chuck and core in either direction relative to a starting position, electrically operable power means to actuate the unit, electrical circuits under the control of limit switches to cause operation of the power means, a mechanism movable with the unit to control the power means whereby a bank wound coil may be wound on the core, and other controls in the mechanism to shorten the rocking motions of the core at the ends of the coil to make the coil uniform throughout its length.

8. In a toroidal coil winding machine having a chuck to support a toroidal core at a given position, and a shuttle, for a supply of wire to be wound on the core, supported for movement in a circular path through the core, power means to drive the shuttle to wind the wire on the core, a unit actuatable by the power means to rock the chuck about the center of the core relative to given limits, electrical circuits controlled by manual switches and mechanically actuatable limit switches, elements selectively energizable at given time intervals under the control of certain of the limit switches by the closing of certain of the manual switches to cause the shuttle to form

layer winding of the wire on the core, and selectively energizable at given intervals under the control of all the limit switches by the closing of another manual switch to cause the shuttle to form bank winding of the wire on the core.

9. In a toroidal coil winding machine having a chuck to support a toroidal core at a given position, and a shuttle, for a supply of wire to be wound on the core, supported for movement in a circular path through the core, power means to drive the shuttle to wind the wire on the core, a unit actuatable by the power means to rock the chuck about the center of the core relative to given limits, electrical circuits controlled by manual switches and mechanically actuatable limit switches, means under the control of the circuits to initially move the chuck and core to one or the other limit for subsequent left or right bank winding of the wire on the core, and elements energizable by certain of the circuits to cause 10 rocking motions of the chuck and core shorter than the distance between the said limits and advancing progressively from the starting limit to the finish limit to cause bank winding of the wire on the core.

10. In a toroidal coil winding machine having a chuck to support a toroidal core at a given position, and a shuttle, for a supply of wire to be wound on the core, supported for movement in a circular path through the core, power means to drive the shuttle to wind the wire on the core, a unit actuatable by the power means to rock the chuck about the center of the core relative to given limits, electrical circuits controlled by manual switches and mechanically actuatable limit switches, means under the control of the circuits to initially move the chuck and core to one or the other limit for subsequent left or right bank winding of the wire on the core, elements energizable by certain of the circuits to cause rocking motions of the chuck and core shorter than the distance between the said limits and advancing progressively from the starting limit to the finish limit to cause bank winding of the wire on the core, and a mechanism under the control of the actuable unit to rock the chuck and core to operate certain of the limit switches to cause the unit to move the core and chuck still shorter distances at the beginning and end of the winding.

11. A toroidal coil winding machine comprising a chuck to support a toroidal core at a given position, a shuttle for a strand to be wound on the core, supported for movement in a circular path through the core, a rocking shaft having the chuck mounted thereon whereby the center of the core will be coincident with the axis of the shaft, a driving unit actuatable to rock the shaft with the chuck and core in either direction, power means to actuate the driving unit, control units to reverse the direction of drive of the driving unit mounted at spaced positions, a member driven by the driving means relative to the control units, and elements supported at variable spaced positions on the member to actuate their respective control units whereby the driving unit will rock the shaft with the chuck and core between variable limits relative to the shuttle to cause formation of coils of various sizes at various positions on the core.

12. A toroidal coil winding machine comprising a chuck to support a toroidal core at a given position, a shuttle for a strand to be wound on the core, supported for movement in a circular path through the core, a rocking shaft having the

5

chuck mounted thereon whereby the center of the core will be coincident with the axis of the shaft, a fluid operable unit to rock the shaft with the chuck and core in either direction relative to a starting position, operable fluid control means to cause actuation of the unit, and means driven by the unit to cause operation of the fluid control means whereby the shaft with the chuck and core may be moved at selected variable speeds relative to the starting position to cause formation of various types of coils on the core.

13. A toroidal coil winding machine comprising a chuck to support a toroidal core at a given position, a shuttle for a strand to be wound on the core, supported for movement in a circular path through the core, a rocking shaft having the chuck mounted thereon whereby the center of the core will be coincident with the axis of the shaft, a fluid operable unit to rock the shaft with the chuck and core in either direction relative to a starting position, electrically operable fluid control means to cause actuation of the unit, electrical circuits under the control of limit switches to cause operation of the fluid control means, and a mechanism movable with the unit to operate the fluid control means in given sequence whereby a bank wound coil may be wound on the core.

14. A toroidal coil winding machine comprising a chuck to support a toroidal core at a given position, a shuttle for a strand to be wound on the core, supported for movement in a circular path through the core, a rocking shaft having the chuck mounted thereon whereby the center of the core will be coincident with the axis of the shaft, a fluid operable unit to rock the shaft with the chuck and core in either direction relative to a starting position, electrically operable fluid control means to cause actuation of the unit, electrical circuits under the control of limit switches to cause operation of the power means, a mechanism movable with the unit to operate the fluid control in given sequence whereby a bank wound coil may be wound on the core, and other controls in the mechanism to shorten the rocking motions of the core at the ends of the coil to make the coil uniform throughout its length.

15. In a toroidal coil winding machine having a chuck to support a toroidal core at a given position, and a shuttle, for a supply of wire to be wound on the core, supported for movement in a circular path through the core, electrically operable fluid control means to drive the shuttle to wind the wire on the core, a fluid operable unit actuatable by the fluid control means to rock the chuck about the center of the core relative to given limits, electrical circuits controlled by a manual switch and mechanically actuatable limit switches, the fluid control means being energized by the closing of the manual switch whereby the shuttle and core may be driven to wind layers of convolutions of the wire on the core, an element energized by certain of the circuits under the control of the limit switches to reverse the motion of the core at the said limits, and a mechanism driven by the unit to actuate the limit switches.

16. In a toroidal coil winding machine having a chuck to support a toroidal core at a given position, and a shuttle, for a supply of wire to be wound on the core, supported for movement in a circular path through the core, electrically operable fluid control means to drive the shut-

60

65

70

75

tle to wind the wire on the core, a fluid operable unit actuatable by the fluid control means to rock the chuck about the center of the core relative to given limits, electrical circuits controlled by manual switches and mechanically actuatable limit switches, elements selectively energizable at given time intervals under the control of certain of the limit switches by the closing of certain of the manual switches to cause the shuttle to form layer winding of the wire on the core, and selectively energizable at given intervals under the control of all the limit switches by the closing

of another manual switch to cause the shuttle to form bank winding of the wire on the core.
